CLAIM

The ornamental design for a combined liquid dispenser and disposable cup holder, substantially as shown and described.

DESCRIPTION

FIG. 1 is a perspective view of a combined liquid dispenser and disposable cup holder showing my new design;

FIG. 2 is a side elevational view taken from the right of FIG. 1;

FIG. 3 is a rear elevational view;

FIG. 4 is a side elevational view taken from the left of FIG. 1;

FIG. 5 is a top plan view.

The bottom is flat and unornamented, except for the opening in the base of the cup holder.
